INTERVAL TIMER

Kenneth M. Kiel, Ann Arbor, Mich., assignor to
 King-Seeley Corporation, Ann Arbor, Mich., a
 corporation of Michigan

Application September 29, 1951, Serial No. 248,935

6 Claims. (Cl. 58—21.13)

1

The present invention relates to an improved interval timer.

In interval timers, it is frequently desirable to move the signal actuating member to one position for actuating the signal and to return the signal actuating member to an at least partially withdrawn position immediately after actuation of the signal means. Interval timers of the type including a bell afford one example of constructions in which it is desirable that the hammer member which strikes the bell be returned to a position in which it is out of engagement with the bell.

It is an object of the present invention to provide an improved construction for interval timers where such return movement of the signal actuating member is desired. More particularly, it is an object of the present invention to provide such an improved construction which is simple in design, reliable and efficient in operation and economical of manufacture.

It is also an object of the present invention to provide an improved interval timer construction of the type including an escapement mechanism for returning the arbor to its zero position and in which a single spring means mounted on the signal actuating member serves both to engage the escapement mechanism to stop movement of the arbor when it reaches the zero position and also to effect the above-mentioned partial return of the signal actuating member from the position in which it actuates the associated signal means.

Other and more detailed objects of the present invention will be apparent from a consideration of the following specification, the appended claims and the accompanying drawings, wherein:

Figure 1 is an elevational view of a timer embodying the present invention, taken from one side thereof and showing the casing and bell removed;

Figure 2 is a sectional view of the construction illustrated in Figure 1, taken along the line A—A thereof; and

Figure 3 is an elevational view of the opposite side of the timer from that illustrated in Figure 1.

Many of the features of construction of the timer illustrated in the accompanying drawings are of generally conventional design and only so much of the construction is illustrated and described in detail herein as is necessary for a full understanding of the features of the present invention. The interval timer to which the present invention relates, and which is shown in the accompanying drawings, is of the type in which the main arbor of the clockwork is provided with a

2

manual control knob (not shown) and the construction and arrangement are such that when the arbor is rotated in one direction from a zero or starting position the signal actuator is cocked. The rate of return of the arbor to the starting position is controlled by the clock mechanism and the signal actuator is tripped upon return of the arbor to the starting position, thus operating a suitable signal.

Referring to the drawings, the present invention is shown incorporated in a timer having a clock mechanism carried by and between a pair of movement plates 10 and 12. The clock mechanism includes a main arbor 14 suitably journaled in the movement plates and connected in the usual manner through a train of gears to a verge-type escapement comprising an escape wheel 16, a verge arm 18, and a balance wheel 20 carried by a balance staff 22. The ends of the balance staff 22 are tapered and fitted into conical bearings 24 and 26 mounted, respectively, in the movement plates 10 and 12. A main spring 28 is mounted on the outer side of the movement plate 10, as best illustrated in Figures 1 and 2, and has its outer end anchored to an outwardly turned projection 30 on the movement plate 10 (see Figure 1) and has its inner end connected to the arbor 14, as illustrated in Figures 1 and 2, by means of a spring anchor plate 32.

It will be appreciated that the spring 28 normally tends to rotate the arbor 14 in a counter-clockwise direction as viewed in Figure 1 and in a clockwise direction as viewed in Figure 3, under the control of the escapement mechanism and associated gear train in the usual manner.

In the preferred embodiment illustrated in the drawings, the mechanism of the timer which operates the signal comprises a short stub shaft 34 secured to the movement plate 12 and on which is journaled a hammer bell crank 36, the shape of which is best illustrated in Figure 3. The bell crank 36 includes an outer arm portion 38 adapted to engage a suitable signal device which in the preferred embodiment illustrated in the drawings is the bell indicated at 40, and an inner arm 42 having an outwardly turned projection 44 extending outwardly through an opening 46 provided in the movement plate 12. A spring 48 is mounted on the plate 12, as indicated at 50, and engages an outwardly turned projection 52 on the outer arm 38 of the signal actuator 36, which projection 52 extends outwardly through an opening 54 provided in the movement plate 12. The movement plate 12 is also provided with an out-

wardly turned projection 56 engaged by the spring 48 in the position of rest to which the signal actuator 36 comes after it is tripped.

The cocking and tripping mechanism comprises a latch 58 which is pivotally mounted on the movement plate 12 by a rivet 60 and is provided with a latching portion 62 adapted to move under the outwardly extending projection 44 on the signal actuator or hammer 36 to hold the hammer 36 in the cocked position. The latch 58 is urged in a counterclockwise direction, as viewed in Figure 3, by a spring 64, one end of which is mounted in the movement plate 12, as indicated at 66, and the other end of which engages an outwardly turned projection 68 on the latch 58. A cam plate 70 is mounted on the arbor 14 and is drivingly connected thereto, as hereinafter described, for engaging the projection 44 of the hammer 36 and pivotally moving the hammer 36 in a counterclockwise direction, as viewed in Figure 3, to a position in which the spring 64 acting against the latch 58 may move the latching portion 62 of the latter into position to engage the projection 44 on the hammer and hold the hammer in cocked position. For this purpose, the cam plate 70 is provided with a cam surface 72. The portion of the arbor 14 upon which the cam plate 70 is mounted is provided with a pair of opposed parallel flats 74, best illustrated in Figure 2. The cam plate 70 is provided with a central opening, generally indicated at 76, receiving the portion of the arbor 14 having the flats 74. This opening 76 is adapted to provide a lost motion connection between the arbor 14 and the cam plate 70 and provide a driving connection between the arbor and the cam plate 70 affording an effective height of the cam surface 72, upon rotation of the arbor in a winding or setting direction (a counterclockwise direction, as viewed in Figure 3), which is sufficient to move the hammer 36 in a counterclockwise direction, as viewed in Figure 3, to its cocked position, in which the latching portion 62 of the latch 58 may be moved into engagement with the projection 44 by the spring 64. Also, the shape of the opening 76 is such that upon rotation of the arbor 14 in the opposite direction, as during the return movement of the arbor to the starting or zero position under the control of the escape mechanism, the cam plate 70 is connected to the arbor 14 and driven thereby with the cam surface 72 having a lesser effective height than during rotation of the arbor in the other direction, so that during such return movement the cam plate 70 does not interfere with the projection 44 on the hammer 36. The cam plate 70, however, is provided with an inwardly turned projection 78 which engages a co-operating outwardly turned projection 80 on the latch plate 58 to pivot the latch plate 58 in a clockwise direction, as viewed in Figure 3, and move the latching portion 62 out of engagement with the projection 44, thereby tripping the hammer 36 and permitting the spring 48 to throw the outer arm portion 38 of the hammer 36 outwardly against the skirt of the bell 40.

The opening 76 in the cam plate 70 may be of any suitable shape providing the above mentioned two different connections between the arbor 14 and the cam plate 70 upon rotation of the arbor 14 in opposite directions. One suitable shape for the opening 76, providing such connections with the arbor 14 at the flats 74 is illustrated in the copending application of Rex

C. Darnell, Serial No. 249,699, filed September 29, 1951, where this feature of construction is illustrated and described in detail and claimed.

The signal actuator device or hammer 36 carries an elongated leaf spring 82, one end of which is mounted on the hammer 36 as illustrated at 84 and the other end of which engages the balance staff 22 when the hammer 36 has been tripped. The mounting of the spring 82 on the hammer 36 is disposed relative to the stub shaft 34, by means of which the hammer 36 is pivotally mounted, so that the loading of the spring 82 produced by the engagement of the outer end of the spring 82 with the balance staff 22, when the hammer 36 is tripped, acts upon the hammer 36 through the mounting 84, to urge the hammer 36 in a counterclockwise direction as viewed in Figure 3.

It will now be appreciated that, after a winding movement of the arbor 14, and a subsequent return movement of the arbor 14 and the cam plate 70 driven thereby, to a position in which the cam plate 70 through the engagement of the flange 78 thereon with the flange 80 of the latch, has moved the latch to the tripped position illustrated in Figure 3, the outer arm portion 38 of the hammer 36 will be thrown outwardly by the action of the spring 48 so that the outer portion 38 moves from the cocked position indicated in broken lines at 86, outwardly to the position indicated in broken lines at 88 and strikes the bell 40. During this movement of the hammer 36 the spring 48 moves into engagement with the stop projection 56 on the movement plate 12, thereby stopping the outward movement of the outer end of the spring 48 while the inertia imparted to the hammer 36 by the spring 48 causes it to continue outwardly to the position indicated at 88 in which it strikes the bell 40. At this time it will be appreciated that the projection 52 has moved outwardly away from and out of engagement with the spring 48 and the spring 82 has moved into engagement with the staff 22 and has been loaded by the continued movement of the hammer 36 outwardly against the bell 40. This loading of the spring 82 acts through the mounting 84 to urge the hammer 36 in a counterclockwise direction, as viewed in Figure 3, to a position in which the outwardly turned projection 52 on the hammer 36 engages the spring 48. The spring 48 and the spring 82 are so proportioned that the hammer 36 comes to rest in the position illustrated in full lines in Figure 3 in which the spring 82 remains in engagement with the balance staff 22, providing a frictional engagement stopping the rotary movement thereof, and also continues to act to hold the hammer 36 in the position illustrated in Figure 3.

While only one specific embodiment of the invention has been illustrated and described in detail herein, it will be readily appreciated by those skilled in the art that numerous modifications and changes may be made without departing from the spirit of the present invention.

What is claimed is:

1. In an interval timer, a main spring, an arbor disposed to be driven in one direction by said main spring and movable in the opposite direction to wind said main spring, escape mechanism for controlling the rate at which said main spring drives said arbor, a signal actuating member movable between first and second positions, means effective upon movement of said arbor in said one direction to a predetermined position for moving said member from said first position to

said second position, and resilient means mounted on said member and operable upon said movement of said member to engage said mechanism to stop the movement of said arbor by said main spring and move said member from said second position toward said first position.

2. The combination as defined in claim 1, wherein said signal actuating member is mounted for pivotal movement, said first named means is effective to produce a moment effecting pivotal movement of said member in one direction, and said last named means is effective upon pivotal movement of said member in said one direction to said second position, to produce a moment effecting pivotal movement from said second position and in the opposite direction.

3. The combination as defined in claim 1 including a bell disposed to be struck by said member upon the latter reaching said second position, and said resilient means being so disposed relative to and mounted on said member that as said member is moved to said second position said resilient means is loaded and acts to produce a moment effective to move said member out of engagement with said bell.

4. The combination as defined in claim 1, wherein said resilient means comprises an elongated cantilever spring having one end rigidly mounted on said signal actuating member and the other end adapted to engage said escape mechanism during said movement of said member to said second position.

5. In an interval timer, a main spring, an arbor disposed to be driven in one direction by said main spring and movable in the opposite direction to wind said main spring, escape mechanism for controlling the rate at which said main spring drives said arbor, a signal actuating member mounted for pivotal movement between first and second positions, means effective upon movement of said arbor in said one direction to a predetermined position for pivoting said member from said first position to said second position, said

means including a spring element engaging said member, and a spring element mounted on said member and including a portion adapted to engage said escape mechanism during said movement of said member from said first position to said second position to stop the movement of said arbor by said main spring, said spring being loaded during said movement of said member and being effective when said member reaches said second position to move said member from said second position toward said first position, the construction and arrangement of said escape mechanism, said member, and said spring elements, and the comparative loading of said spring elements being such that said member is moved from said second position to and comes to rest at a final position intermediate said first and second positions in which the moments exerted on said member by said spring elements are equal and said portion of said last named spring element remains in engagement with said escape mechanism.

6. The combination as defined in claim 5, wherein said second named spring element is an elongated cantilever spring having one end rigidly mounted on said member and the other end free when said member is in said first position and adapted to engage said escape mechanism to stop said arbor and load said second named spring element during said movement of said member to said second position.
